UNITED STATES PATENT OFFICE.

JOSEPH KELLER AND HENRY KÜNSTLICH, OF NEW YORK, N. Y.

THERMOSTAT.

Application filed February 21, 1924. Serial No. 694,437.

To all whom it may concern:

Be it known that we, JOSEPH KELLER and HENRY KÜNSTLICH, first named a citizen of U. S. A., and second named a citizen of no country, residing at New York, in the county of New York and State of New York, have invented certain new and useful Improvements in a Thermostat, of which the following is a specification.

10 This invention appertains to alarms or signals and the primary object of the invention is to provide an improved device, for giving an alarm automatically when the temperature of the building or room in which the device is situated exceeds a predetermined amount or value.

Another object of the invention is the provision of a fire alarm or signal embodying a casing having mounted therein a stationary contact and a weighted movable contact, the weighted movable contact being normally held in a raised position in spaced relation to the rigid contact by a fusible pin, which is adapted to melt at a predetermined 25 temperature, thereby permitting the weighted contact to fall in engagement with the stationary contact and thus close a suitable alarm circuit.

A further object of the invention is the provision of a test circuit for the improved fire alarm or signal whereby the working condition of the system can be found with a minimum amount of time and labor.

A still further object of the invention is to provide an improved device of the above character, which will be durable and efficient in use, one that will be simple and easy to manufacture and one which can be placed upon the market at a small cost.

40 With these and other objects in view, the invention consists in the novel construction, arrangement and formation of parts, as will be hereinafter more fully described, claimed and illustrated in the accompanying drawings, in which drawings:

Figure 1 is a perspective view of the improved device.

50 Figure 2 is a longitudinal section through the same taken on the line 2—2 of Figure 1.

Figure 3 is a transverse section through the device taken on the line 3—3 of Figure 1, and

55 Figure 4 is a diagrammatic view showing the circuit of the improved device.

Referring to the drawings in detail, wherein similar reference characters designate corresponding parts throughout the several views, the letter A generally indicates the improved device, which comprises a casing 5, which can be formed of any desired material and this casing 5 includes a front and rear wall 6 and 7, a top and bottom wall 8 and 9, and an end rigid wall 10. The opposite end of the casing is closed by a hinged door 11, which can be maintained in its closed condition by a suitable lock 12. Rockably mounted within the casing upon a suitable bolt or pin 13, is a contact lever 14. This bolt or pivot pin 13 is secured to a suitable block of insulation or fireproof material, such as asbestos 15. This block 15 can be held in place by a suitable machine screws 16 which are adapted to extend through the block into lugs 17 formed on the rear wall 7. The end of the lever opposite to the pivoted end thereof is provided with an enlargement 18 which constitutes a weight for normally urging said lever 14 downwardly toward a rigid contact bracket 19. This bracket 19 is secured to the block 15 and is of an angle shape in side elevation. The terminal of the lever 14 adjacent to the pivot bolt or pin 13 has connected therewith by the use of a suitable screw or the like 20 a line wire 21, while the bracket 19 has secured thereto by the use of a suitable screw 22 or the like a line wire 23. The line wire 21 is connected to one pole of a suitable battery 24, which can consist of one or more dry cells, and the line wire 23 is connected to the other end of this battery. The line wire 23 has interposed in the length thereof a suitable signalling device such as an alarm bell 25 or a siren horn.

In order to hold the lever 14 in a raised position above the angle bracket contact 19, a socket 26 is carried by the weighted end of the lever, which is adapted to receive a soft fusible metal or alloy pin 27 which can be inserted into the socket 26 through a suitable opening in the front wall 6 of the casing 5.

It is obvious that when the pin is subjected to heat above a predetermined value, that the pin will melt and thus permit locking of the lever 14 in engagement with the angle contact bracket 19 and thus close the circuit through the bell 25 or siren horn and

the sounding of the bell or the horn will indicate to persons that the house is on fire.

If so desired a second rigid contact 28 can be provided and this contact is carried 5 by the block 15 and when the lever is in its raised position the same will be in engagement therewith. This rigid contact 28 has electrically connected thereto a feed wire 29 which is connected with the line 10 wire 23. This wire 23 has interposed in the length thereof a small indicating lamp 30 and in advance of the lamp a single throw switch 31. It is obvious that when the switch 31 is in its closed position and the 15 lever 14 in its raised position, that the circuit can be tested to see if the battery 24 is in proper working condition. It can be seen of course that if the lamp 30 gives its usual light that the battery is in proper 20 condition.

From the foregoing description, it can be seen that we have provided an improved device of simple and durable construction for giving an alarm in case of fire.

25 Changes in details may be made without

departing from the spirit or the scope of this invention.

What we claim as new is:

In a fire alarm, a closed casing, a face plate of insulating material rigidly secured 30 in the casing in spaced relation to the front wall thereof, a lever rockably mounted at one end on said face plate intermediate the face plate and the front wall, a head formed on the free end of the lever, a stationary 35 electric conducting bracket disposed in the path of said head carried by said face block, an outwardly extending removable socket carried by said head, the front wall of the casing being provided with an opening, and a fusible plug arranged to fit in the opening and in said socket for holding the free end of the lever in a raised position above said bracket, the outer end of the alloy pin extending outwardly of the casing. 40 45

In testimony whereof we affix our signatures:

JOSEPH KELLER.
HENRY KÜNSTLICH.
